[57] CLAIM

The ornamental design for a boat mooring hook, as shown.

DESCRIPTION

FIG. 1 is a side view of a boat mooring hook embodying the present design therefor;

FIG. 2 is a front elevational view of a boat mooring hook as seen from the right-hand side of FIG. 1;

FIG. 3 is a top plan view of the same as seen from above in FIG. 2;

FIG. 4 is a back elevational view of a boat mooring hook as seen from the left-hand side of FIG. 1;

FIG. 5 is a perspective view of a boat mooring hook, showing the back and side opposite to that of FIGS. 1 and 2 from an angle of about 45°; and

FIG. 6 is a bottom plan view of a boat mooring hook looking upward from below in FIG. 2.

Fig. 6.
